CLAIM

The ornamental design for a button panel, as shown and described.

DESCRIPTION

FIG. 1 is an isometric view of a button panel in accordance with the invention; and,

FIG. 2 is top plan view of the button panel illustrated in FIG. 1.

The dash-dash broken lines depict portions of the button panel that form no part of the claim, while all other broken lines depict the environmental and gaming machine structure and form no part of the claim. The surface shown between the solid lines and the broken lines forms no part of the claim.

1 Claim, 1 Drawing Sheet(56)
